UNITED STATES PATENT OFFICE.

SHELTON J. GUNN, OF GUNNTOWN, FLORIDA.

AUTOMATIC MACHINE FOR SHAPING AND FASTENING IRON BANDS TO BOX MATERIAL.

Application filed March 17, 1922. Serial No. 544,565.

To all whom it may concern:

Be it known that I, SHELTON J. GUNN, a citizen of the United States, residing at Gunntown, in the county of Levy and State 5 of Florida, have invented certain new and useful Improvements in Automatic Machines for Shaping and Fastening Iron Bands to Box Material, of which the following is a specification.

10 This invention relates to an automatic machine for shaping and fastening iron bands to box material, such as box-covers.

The object of the invention is automatically to feed the material for making boxes, 15 having particular reference to covers, through the machine, and simultaneously feeding metal strips for reinforcing the ends of the cover through the machine with the cover, shaping the metal strips around the 20 ends of the cover, after which the cover and metal strips are fed through the pressure-dies, where the metal strips are perforated and the metal strips and cover pressed together, and finally severing the strips and 25 passing the completed article beneath a receiving rack, the final operation being to transfer the stacked reinforced covers to a receiving table where they may be compressed and tied for shipment.

30 In the accompanying drawings:—

Fig. 1 is a side elevation of the machine; Fig. 2 is a top plan view;

Fig. 3 is a transverse section on line 3—3 of Fig. 1;

35 Fig. 4 is a longitudinal sectional view through the machine;

Fig. 5 is an enlarged end view of the machine partly in section disclosing the feeding-hopper;

40 Fig. 6 is an end view of the rear of the machine partly in section, showing the receiving table;

Fig. 7 is a detail perspective view of the end of the reciprocating carriage disclosing 45 the transfer table;

Fig. 8 is an enlarged side elevation of the assembling-rack;

Fig. 9 is a fragmentary transverse sectional view on line 9—9 of Fig. 8;

50 Fig. 10 is an enlarged sectional view through one portion of the lifting mechanism;

Figs. 11, 12 and 13 are enlarged views dis-

closing the first set of forming rolls for the metal strips;

55 Figs. 14, 15, 16 and 17 are views showing the second set of forming rolls and forming-blocks;

Fig. 18 is a detail plan view of the upper 60 pressure dies;

Fig. 19 is a detail front elevation of the pressure dies, parts thereof being shown in section;

Figs. 20 and 21 are transverse views 65 through the pressure-dies shown in different positions;

Fig. 22 is a detail view of one end of the cover, showing the metal strip as applied thereto;

Fig. 23 is an enlarged detail view of one 70 of the spring-pressed dogs carried by the reciprocating carriage.

The machine consists of a main frame, comprising parallel side-bars 1, 1, and end members 2, 2, supported at each end by 75 suitable adjustable legs 3. Arranged within the main frame is a reciprocating carriage consisting of parallel bars 4, supported by suitable guideways 5 supported by suitable transfer members 6, 6, arranged across 80 the main frame. The carriage is actuated by means of a cam 7 keyed to the shaft 8, the latter being geared to the main drive-shaft 9 by suitable gears 10 and 11. The 85 main drive is driven by belt-pulleys 12. The said driving means is journaled in suitable standards 13, 13, mounted upon the base 14, the upper ends of said standards being connected together by suitable cross-beams 15.

Arranged longitudinally of the machine, 90 and supported upon the base 14 is a beam 16, to which is pivoted a rocking-beam 17, the upper end of which is pivotally connected to the reciprocating carriage by means of a yoke 18. The rocker-beam 17 in turn is 95 connected by connecting-rod 19 to an eccentric strap 20 which surrounds the cam 7. In this manner the carriage is given a constant reciprocating movement.

Arranged at the forward end of the main 100 frame and above the reciprocating carriage is a feeding hopper comprising a rack-frame 21 provided with a plurality of vertical guide-members 22 forming a receptacle for the material or covers to which the reinforcing metal is to be applied. Arms 23

are pivoted as at 24 to the main frame 21, having their upper ends 25 bent inwardly over the material in the hopper. Connected to the outer ends of the arms 23 are actuating-rods 26, which extend downwardly and connect to a foot-lever 27, pivoted as at 28 to the supporting-beam 16. A spring 30 secured as at 31 to one end of the main frame, and as at 32 to the foot-lever 27, serves to hold the arms 23 under tension, whereby the covers are fed downwardly as they are taken from the under side of the pile in the feeding hopper, as hereinafter described.

When re-filling the hopper, the foot-lever 27 is pressed downwardly, swinging the arms 23 laterally, permitting the hopper being readily re-filled. Extending forwardly of the hopper on each side of the machine is a set of bending rolls adapted to receive the strips of metal which are to be fed simultaneously through the machine with the covers. The first set of rolls 33 and 34 are pivotally mounted upon vertical studs at a slight angle, the parallel surfaces adapted to receive the metal strips 35 edgewise, as illustrated in Fig. 11. The next set of rolls consists of male and female rolls 36 and 37, so shaped as to bend the metal slightly, as illustrated in Fig. 12. The next set of rolls 30 consists of male and female rolls 38 and 39, so shaped as to impart substantially a right-angle bend in the metal band 35. These strips are preferably fed to the machine by a pair of reels 40, as disclosed in Fig. 1.

The cover to be reinforced is removed from the hopper by a set of spring-actuated dogs 41 carried by the reciprocating carriage, which, as shown in Fig. 2, are in position to remove the lowermost cover from the hopper. The rearward stroke of the carriage is so regulated as to carry the cover together with the metal strip 35 a certain distance toward the rear of the machine. The metal strips and the edges of the cover pass through another set of bending blocks 42. These blocks serve as guides for the set of bending-rolls 43 and 44, serving to bend the metal strips at a more acute angle around the edges of the cover. Another set of bending rolls 45 and 46 are placed ahead of the rolls 43 and 44, serving to bend the metal strips 35 more about the edges of the cover, as shown in Fig. 16, and finally the strips and the cover are passed through a set of bending blocks 48, having a substantially U-shaped opening 49 therein, serving to press the metal strips 35 snugly around the edges of the material as disclosed in Fig. 17. Arranged at the open end of the U-shaped opening 49 are a set of upper and lower guide members 50, which serve to position the metal strip evenly around the edges of the cover.

The carriage having traveled a sufficient

distance to place the cover in the position opposite the last-mentioned set of rolls, moves forward again. The cover, which has previously been placed before the second set of bending-rolls is prevented from moving back by suitable stops 51 carried by the main frame. As the carriage moves forward, another cover is taken from beneath the pile in the feeding-hopper, and the spring-actuated dogs 52 carried by the reciprocating carriage in turn move the first cover rearwardly a sufficient distance to place the same beneath a set of dies, where the metal strips are punched and forced together against the cover.

These dies preferably consist of a set of stationary members 53 suitably supported upon supports 53' carried by a transverse beam 54, adjustably supported in brackets 55 extending inwardly from the standards 13, 13. Adjustable stops 56 carried by the brackets 55 serve as a means for vertically adjusting the beam 54.

Mounted vertically upon the member 53 are suitable studs 57, which guide a vertical movable member 58 secured by supports 59 to a transverse vertical movable beam 60. This beam 60 is guided for vertical movement in suitable slots in the standards 13, 13, having secured on either end thereof connecting-rods 61, which in turn are actuated by cams 62 keyed to the secondary driveshaft 8.

As clearly shown in Figs. 18, 19, 20, and 21, the stationary member 53 of the dies has secured to the upper side thereof a bar 63. Arranged along the inner edge of this bar are a plurality of punches 64, the lower ends 65 thereof being squared and received in a slot 66 running longitudinally of the member 53, thereby insuring the proper alignment of the several punches. A vertically movable stripper bar 67 is arranged directly above the slot 66 normally covering the upper ends of the punches 64, being held in spaced relation to the member 53 by means of headed studs 68, the body portions of which are surrounded by spiral springs 69.

A guide-member 70 is arranged longitudinally of the member 53, serving to position properly the box cover and metal strips 35 over the punches 67. The member 58 carries a similar bar 71 which likewise carries a plurality of punches 72, the inner ends 73' thereof being squared and received in a longitudinal slot 74' in the member 58. The outer ends of the punches are likewise protected by a stripper-bar 75' supported in spaced relation to the member 58 by suitable headed studs 76' surrounding which are springs 77'.

Arranged at the extreme ends of the bar 71, and at intervals longitudinally thereof are prick punches 78', these punches serving to pierce the metal strips 35 at the extreme

ends thereof, which ends are adapted to extend beyond the cover proper, and likewise punch holes at intervals along the strip and box cover, forming nail holes for finally securing the cover in place.

From the above disclosure, it will be seen that the upper member 58 is forced downwardly at a predetermined time, forcing the first-mentioned punches 64 and 72 through 10 the metal strip and into the material, as clearly shown in Fig. 21, the punches 64 and 72 being slightly offset, as shown in Figs. 20 and 21.

Fig. 22 shows the operation as completed 15 at this point. To assist in holding the material in place as it is fed beneath the dies, I preferably provide two parallel strips 73, which lie parallel and adjacent to the dies being bent up at one end and secured as at 20 74 to the transverse bars 75 supported by the standards 13, 13, the cover passing beneath this strip as it passes beneath the dies.

In the last operation, the metal strips 35 having been securely fastened to the edges 25 of the cover, it is now desirable to sever the continuous strip and stack the different covers after being reinforced. To accomplish this, I preferably arrange a plurality of vertical standards 76 secured to the main 30 frame 1, 1, forming an assembling-rack. These standards have pivoted to their extreme upper ends dogs 77. The lower ends 78 of these dogs extend through openings 35 in the standards being held in that position by springs 79, as shown in Figs. 8, 9 and 10.

As illustrated in Fig. 4, the cover is raised from the carriage a sufficient height to be received by the dogs 77, the following mechanism preferably being used to accomplish 40 this. The numeral 80 indicates guide-members secured to the main frame 1, 1, on either side of the machine. Carried by these guides are vertically movable members 81 having secured to the upper ends thereof a horizontal bar 82, provided at its outer ends with upwardly-projecting lift fingers 83. These fingers are adapted to be moved vertically at a predetermined time by means of a rock- 45 shaft 85 suspended beneath the main frame by suitable supporting-brackets 86. Extending horizontally from this rock-shaft are rocker-arms 87, the outer ends of which are received between the set of rollers 88 and 89 contained in the housing 90 secured to the vertically movable member 81.

Depending from the rock-shaft 85 is a rocker-arm 91, the lower ends of which are forked as at 92, and extending transversely 50 thereof, is a cross-pin 93 received in an elongated slot 94 arranged in the reciprocating-bar 95, the opposite end of which is pivoted to the rocking-beam 17 by which a reciprocating motion is imparted to the bar 95. The slot 94 is offset toward the rear

of the bar, forming an abutment 93', which, when the bar 95 is reciprocated, imparts a rocking motion to the rocker-arm 87, the latter imparting a vertical movement to the lift-fingers 83, serving to lift the cover vertically from the reciprocating carriage and deposit the same upon the dogs 77. Prior to this movement, however, a cutter 96 carried by the vertically movable die 58 has severed the metal strips 35, permitting the 75 material to be moved vertically from the carriage.

To position accurately the material between the vertical standards 76, I preferably arrange stop-pins 97 upon the main frame 80 1, 1, and, to prevent the material from bulging when coming in contact with the stops 97, I preferably arrange a set of stop-fingers 98, which are secured to the rock-shaft 85. The upper ends of these fingers are 85 bent inwardly as at 98', and the outer end of the board passing to this position is received beneath the ends of the rocking-fingers.

As observed in Fig. 8, the lift-fingers 83 90 are beneath the cover about to be lifted a sufficient distance to permit the rocker-fingers 98 being moved out of engagement with the box before the lift-fingers 83 are effective.

The severed metal strips 35, which reinforce the material about to be lifted are of such a length as to extend horizontally from the cover, and it is desirable to bend them downwardly when the cover is being lifted. To accomplish this, I preferably arrange a 100 frame 99 secured at the base of the vertical standards 76, the outer ends of this frame being bent into substantially U-shaped form to receive the set of rolls 100.

As the cover is positioned at this point, the metal strips 35 are directly beneath the rolls 100; as the cover is moved vertically, the ends of the metal strips are bent downwardly by the rolls as the box is moved upwardly, shaping the metal strips as desired, forming extensions whereby the cover may be fastened in place when assembled upon the box.

After a specified number of covers have 115 been collected in the assembling-rack, it is desirable to place them bodily upon a stationary platform, where they may be suitably tied up for shipment.

To accomplish this, I arrange on the reciprocating carriage a collapsible table 101, which is supported for vertical movement upon suitable parallel legs 102. This table 101 normally rests upon the reciprocating table, being of such a height when down to pass beneath the covers being assembled upon the assembling-rack. To raise this table at predetermined times, a pair of arms 103 are pivoted for horizontal movement, as at 104, to the main frame. These arms 120 125 130

are connected by a cross-link 105 in such a manner as to be moved simultaneously. Rollers 106 are secured to the inner ends of these arms, which are adapted to be moved into the path of the depending abutments 107 carried by the table 101, serving to lift the table to a vertical position at predetermined times. To raise this table vertically, I arrange at the rear of the main frame a ratchet-wheel 108 adapted to be actuated by a ratchet-pawl 109 carried by a rocker-arm 110.

Projecting laterally from the reciprocating carriage is an actuating pin 111, which engages the rocker-arm 110 each time the carriage completes a cycle, serving to rotate the ratchet-wheel 108, one notch at a time. A projection 112, Fig. 2, secured to the face of the ratchet-wheel engages the outer end of one of the arms 103, once every revolution of the ratchet-wheel 108, serving to move the rollers 106 into the path of the abutment 107 carried by the transverse table, causing the table to be lifted beneath the covers now assembled upon the assembling-rack.

In order that the table may be held in a vertical position, while moving rearwardly with the covers, I preferably provide a pair of pivoted catches 113 arranged at the extreme rear of the reciprocating carriage. These catches are provided with notches 114 which engage the supports 102 of the transfer table holding the table in vertical position. The catches 113 are tied together with a connecting-link 115, whereby they are actuated simultaneously. To disengage the notches at the proper time to allow the table to collapse, a tripping-dog 116 carried by the main frame is adapted to engage the outer end of one of the catches 113, and a pin 117 extending inwardly from the main frame engages one of the supporting-legs 102 of the transfer table, causing the table to fall to a folded position. The covers carried by the table drop upon suitable stationary supports 118 projecting upwardly from the main frame.

The stack of covers are now in position to be compressed and tied. To compress these, properly, preparatory to tying, I have arranged on either side of the main frame a pair of folding presser-arms 119, which are pivoted to a vertically movable horizontal bar 120 received in slots 121, in the lower depending ends of the stationary supports 118. The lower ends of the arms 119 are bent inwardly, the inner ends thereof being connected by links 122 to a foot-lever 123 pivoted as at 124 to the supporting-beam 16. This foot-lever 123 is held normally in an upright position by spring 124, the spring being of sufficient tension to hold the arms normally in their extended position. Springs 125 assist in causing the

arms 119 to swing inwardly, as pressure is applied to the foot-lever 123. The upper ends 126 of the arms 119 are bent inwardly and adapted to engage the uppermost cover of the pile compressing the several covers together preparatory to being tied.

Operation.

Assuming that the feeding-hopper 21 is filled with the several covers to be reinforced, the reinforcing bands 35 are initially fed through the first set of shaping rolls by hand, and the machine is given a sufficient movement to pass one of the covers to be reinforced together with the reinforcing strips to the second set of forming rolls.

The machine is again given a slight movement, sufficient to pass this board together with the reinforcing strips beneath the pressure and puncturing dies 53 and 58, where the metal strips are pressed and pierced, as disclosed in Fig. 22. The machine is now ready for continuous operation. The reciprocating carriage is adapted to eject a single cover at predetermined intervals from the feeding hopper, and pass it, step by step, through a second set of forming-rolls, thence to the pressing and punching rolls, and finally beneath the assembling rack.

After the cover, which is now reinforced, has been placed beneath the assembling-rack, the reciprocating carriage returns to complete another operation, and simultaneously with this movement the presser and punching dies 53 and 58 are brought together. Simultaneously with this movement the shearing-knife 96 serves to sever the reinforcing strip, which is now beneath the assembling rack, from the continuous metal strips. The mechanism for actuating the lift-fingers 83 is so timed as to elevate at this time the now-severed reinforced cover vertically, where it is received and held between the spring-actuated dogs 77, and simultaneously with this movement, as explained, the outer ends of the reinforcing metal strips 35 are bent downwardly, forming detaching laps.

As the machine continues to operate, the several covers are passed through the different operations explained, and are consecutively elevated to the assembling-rack. The vertically-movable transfer table carried by the reciprocating carriage is normally down in its inoperative position, in which position it is passed beneath the assembling-rack without disturbing the contents thereof. The reciprocating carriage, however, serves to actuate the ratchet mechanism, which in turn, at predetermined intervals, causes the arms 103 which are pivoted for horizontal movement to be brought into the path of the transfer-table 101, at such a time as to cause it to raise vertically when beneath the several reinforced covers which are now stacked

in the assembling-rack, this vertical movement serving to raise the stack above the spring-pressed fingers 77, which, when relieved of the load, retract, permitting the transfer carriage to carry the stack of covers rearwardly into registration with the stationary receiving-table comprised of the stationary supports 118.

As the transfer table reaches this position, suitable tripping mechanism carried by the reciprocating carriage co-operating with the stationary trip 116, unlatches the now vertically raised transfer carriage, which, in turn, is struck by the stationary actuating pins 117, causing the same to drop and deposit its load upon the stationary table, the machine in the meantime continuing in its operation.

During the re-assembling of the reinforced covers upon the assembling-rack, the operator (by manual means consisting of the pivoted arms 119 and the spring-actuated foot-lever 123) compresses the load deposited upon the stationary table preliminary to tying the same sufficiently for the shipment.

It will thus be seen that I have constructed a machine for partially forming the metal reinforcing strips into the proper shape, feeding them past the stacked covers to be reinforced, passing the cover to be reinforced, and the partially formed reinforcing strips through a set of forming rolls, thence to a set of pressing and punching dies, thence to an assembling-rack, and finally transferring the assembled reinforced covers to a stationary rack for bundling and tying.

I claim:

1. A machine of the class described, including a bed, a holder for stacked covers, means for forming metal reinforcing strips around the ends of said covers, a puncturing means, means to feed the reinforced covers in single succession from the holder to the forming means and puncturing means, and means for severing the continuous metal reinforcing strips after passing from the puncturing means.

2. A machine of the class described including a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, and common means to feed the covers and metal reinforcing strips to the metal forming means and thence to the cutting means.

3. A machine of the class described including a bed, a holder for stacked covers, means for forming metal reinforcing strips around the ends of said covers, a puncturing means, means to feed the reinforced cov-

ers in single succession from the holder to the forming means and puncturing means, means for severing the continuous metal reinforcing strips after passing from the puncturing means, and means for assembling the reinforced covers.

4. A machine of the class described including a bed, a holder for stacked covers, shaping rolls arranged in front of the holder for shaping continuous strips of reinforced metal preparatory to being fed past the lowermost cover within the holder, means for forming and bending the metal reinforcing strips around the ends of said covers, means for puncturing the metal reinforcing strips after being formed around the ends of the covers, a common means to feed the covers and metal reinforcing strips to the forming means, thence to the puncturing means, and means for severing the continuous metal reinforcing strip after passing through the puncturing means.

5. A machine of the class described including a bed, a holder for stacked covers, means for shaping continuous strips of reinforcing metal preparatory to being fed past the holder for the covers, means for forming the reinforcing metal strip around the ends of said covers, a cutting means for severing the continuous metal reinforcing strip, an assembling means for the reinforced covers, and a common means to feed the covers and metal reinforcing strips to the metal forming means, thence to the cutting means, thence to the assembling means.

6. A machine of the class described including a bed, a holder for stacked covers, means for shaping continuous strips of reinforcing metal preparatory to being fed past the holder for the covers, means for forming the reinforcing metal strip around the ends of said covers, a cutting means for severing the continuous metal reinforcing strip, an assembling means for the reinforced covers, a common means to feed the covers and metal reinforcing strips to the metal forming means, thence to the cutting means, thence to the assembling means, and means for transferring the covers from the common feeding means to the assembling means.

7. A machine of the class described including a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, a common feeding means to feed the covers and metal reinforcing strips to the metal forming means, and thence to the cutting means, an assembling means adjacent the cutting means and arranged

above the common feeding means, and vertically movable means for transferring the reinforced cover from the common feeding means to the assembling means.

the stationary table, and manual means for compressing the covers after being transferred to the stationary receiving table.

means to the assembling means.

5 8. A machine of the class described including a bed, a holder for stacked covers, means for shaping continuous strips of reinforcing metal preparatory to being fed past the holder for the covers, means for

10 forming the reinforcing metal strips around the ends of said covers, a cutting means for severing the continuous metal reinforcing strip, a common feeding means to feed the covers and metal reinforcing strips to

15 the metal forming means, and thence to the cutting means, an assembling means adjacent the cutting means and arranged above the common feeding means, vertically movable means for transferring the reinforced cover from the common feeding means to the assembling means, a stationary receiving table, and means for transferring the stacked covers from the assembling means to the stationary table.

20

11. A machine of the class described including a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, a common feeding means to feed the covers and metal reinforcing strips to the metal forming means, and thence to the cutting means, an assembling means adjacent the cutting means and arranged above the common feeding means, a vertically movable means for transferring the reinforced cover from the common feeding means to the assembling means, a stationary receiving table arranged at the rear of the machine, means carried by the common feeding means for transferring stacked covers from the assembling means to the stationary table, and manual means for compressing the covers after being transferred to the stationary receiving table.

25 9. A machine of the class described including a bed, a holder for stacked covers, means for shaping continuous strips of reinforcing metal preparatory to being fed past the holder for the covers, means for
30 forming the reinforcing metal strips around the ends of said covers, a cutting means for severing the continuous metal reinforcing strip, a common feeding means to feed the covers and metal reinforcing strips to
35 the metal forming means, and thence to the cutting means, an assembling means adjacent the cutting means and arranged above the common feeding means, a vertically movable means for transferring the
40 reinforced cover from the common feeding means to the assembling means, a stationary receiving table arranged at the rear of the machine, and means carried by the common feeding means for transferring stacked covers from the assembling means to the stationary table.

12. A machine of the class described including a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, and means for transferring the reinforced covers from the reciprocating carriage to the assembling means.

10. A machine of the class described including a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, a common feeding means to feed the covers and metal reinforcing strips to the metal forming means, and thence to the cutting means, an assembling means adjacent the cutting means and arranged above the common feeding means, vertically movable means for transferring the reinforced cover from the common feeding means to the assembling means, a stationary receiving table, means for transferring the stacked covers from the assembling means to

13. A machine of the class described including a main frame, a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, and vertically movable means carried by the main frame for lifting the reinforced covers from the reciprocating carriage to the assembling means.

14. A machine of the class described including a main frame, a bed, a holder for stacked covers, means for shaping continu- 130

ous strips of reinforcing metal preparatory to being fed past the holder for the covers, means for forming the reinforcing metal strips around the ends of said covers, a cut-

5 ting means for severing the continuous metal reinforcing strip, an assembling means for the reinforced covers, a reciprocating carriage provided with a plurality of spaced dogs adapted to feed the covers and metal rein-
10 forcing strips step by step from the holder to the metal forming means, thence to the cutting means, vertically movable means carried by the main frame for lifting the reinforced covers from the reciprocating carriage to the assembling means, and a stationary receiving-table arranged at the rear of the main frame, a vertically movable transfer table carried by the reciprocating carriage adapted to transfer the stacked reinforced covers from the assembling means at predetermined intervals to the stationary receiving table.

15. A machine of the class described including a main frame, a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, vertically movable means carried by the main frame for lifting the reinforced covers from the reciprocating carriage to the assembling means, a stationary receiving table arranged at the rear of the main frame, a vertically movable transfer table carried by the reciprocating carriage, means carried by the main frame and actuated by the reciprocating carriage for raising the vertically movable table at predetermined intervals to transfer the stacked reinforced covers from the assembling means to the stationary receiving table.

16. A machine of the class described including a main frame, a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, means carried by the

main frame and actuated by the reciprocating carriage for transferring the reinforced covers to the assembling means when therebeneath, a stationary receiving-table, a vertically movable transfer table carried by the reciprocating carriage, and means actuated by the reciprocating carriage for tripping the transfer table when in registry with the stationary table for depositing the reinforced covers upon the stationary table. 75

17. A machine of the class described including a main frame, a bed, a holder for stacked covers, means for shaping continuous strips of reinforcing metal preparatory to being fed past the holder for the covers, means for forming the reinforcing metal strips around the ends of said covers, a cutting means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, vertically movable means carried by the main frame for lifting the reinforced covers from the reciprocating carriage to the assembling means, and a common actuating means imparting a co-operative movement to the reciprocating carriage, the cutting means and the vertically movable means.

18. A machine of the class described including a main frame, a bed, a holder for stacked covers, means for shaping continuous strips of reinforcing metal preparatory to being fed past the holder for the covers, means for forming the reinforcing metal strips around the ends of said covers, a means for severing the continuous metal reinforcing strip, an assembling means for the reinforced covers, a reciprocating carriage provided with a plurality of spaced dogs adapted to feed the covers and metal reinforcing strips step by step from the holder to the metal forming means, thence to the cutting means, vertically movable means carried by the main frame for lifting the reinforced covers from the reciprocating carriage to the assembling means, a common actuating means imparting a co-operative movement to the reciprocating carriage, the cutting means and the vertically movable means, a stationary receiving table arranged at the rear of the main frame, and a vertically movable transfer table carried by the reciprocating carriage adapted to transfer the stacked reinforced covers from the assembling means to the stationary receiving table.

19. A machine of the class described including a main frame, a bed, a holder for stacked covers, means for shaping continuous strips of reinforcing metal preparatory to being fed past the holder for the

covers, means for forming the reinforcing metal strips around the ends of said covers, a cutting means for severing the continuous metal reinforcing strip, an assembling means 5 for the reinforced covers, a reciprocating carriage provided with a plurality of spaced dogs adapted to feed the covers and metal reinforcing strips step by step from the holder to the metal forming means, thence 10 to the cutting means, vertically movable means carried by the main frame for lifting the reinforced covers from the reciprocating carriage to the assembling means, a common actuating means imparting a co- 15 operative movement to the reciprocating carriage, the cutting means and the vertically movable means, a stationary receiving table arranged at the rear of the main frame, means carried by the main frame and actuated by 20 the reciprocating carriage for raising the vertically movable means when beneath the assembling means, and means for tripping the vertically movable means when in registry with the stationary receiving table for depositing the reinforced covers upon the stationary receiving table. 25 20. A machine of the class described including a main frame, a bed, a holder for stacked covers, means for shaping continuous strips of reinforcing metal preparatory to being fed past the holder for the covers,

means for forming the reinforcing metal strips around the ends of said covers, a cutting means for severing the continuous metal reinforcing strip, an assembling means 35 30 for the reinforced covers, a reciprocating carriage provided with a plurality of spaced dogs adapted to feed the covers and metal reinforcing strips step by step from the holder to the metal forming means, thence 40 to the cutting means, vertically movable means carried by the main frame for lifting the reinforced covers from the reciprocating carriage to the assembling means, a common actuating means imparting a co-operative movement to the reciprocating carriage, the cutting means and the vertically movable means, a stationary receiving table arranged at the rear of the main frame, means carried by the main frame and actuated by 45 50 the reciprocating carriage for raising the vertically movable means when beneath the assembling means, means for tripping the vertically movable means when in registry with the stationary receiving table for depositing the reinforced covers upon the stationary receiving table, and manual means for compressing the reinforced covers deposited upon the stationary receiving table preparatory to tying. 55 60
